UNITED STATES PATENT OFFICE.

JOACHIM WILKE, OF GARRETT, INDIANA.

TRUSS.

SPECIFICATION forming part of Letters Patent No. 388,608, dated August 28, 1888.

Application filed February 27, 1888. Serial No. 265,499. (No model.)

To all whom it may concern:

Be it known that I, JOACHIM WILKE, a citizen of the United States, residing at Garrett, in the county of De Kalb and State of Indiana, 5 have invented certain new and useful Improvements in Trusses; and I do declare the following to be a full, clear, and exact description of the invention, such as will enable others skilled in the art to which it appertains to make and use 10 the same, reference being had to the accompanying drawings, and to the letters and figures of reference marked thereon, which form a part of this specification.

My invention relates to trusses, and has for 15 its object to provide an arrangement of belts and pads which give entire freedom of movement to the wearer without any danger of displacing the pads.

The invention consists of certain arrangements and constructions of parts, hereinafter described, and particularly pointed out in the 20 claims.

In the accompanying drawings, Figure 1 is a perspective view of my improved truss. 25 Fig. 2 is a full-sized section of one of the pads. Fig. 3 is a side elevation of one of the springs.

The pads are mounted upon a plate, A, preferably of stout leather, and provided at 30 each end with a buckle or a hook for the attachment of a belt, B, of elastic material. Near each end of the plate are three slots, a. These two pads are each provided with a base-plate, C, of metal, which has a lug, c, 35 near its top and another near its bottom. When the plate is made of sheet metal, the lugs may be formed by taking a fold in the sheet, as illustrated in Fig. 2. These lugs are passed through the slots a in the plate A, and 40 a spring pin or staple, C', is then inserted into suitable holes in the lugs c, thereby securely attaching the pads to the plate, but enabling them to be readily removed when desired.

Clamped between the base-plate C and another metallic plate, C', is a leather or cloth cover, D, which is suitably padded with hair to form a cushion, d, and is held distended by means of springs E. These springs are M-shaped, as shown in Fig. 3, having at each 50 angle a coil, e. Several of these springs are

arranged side by side in each pad, their fixed ends being secured alternately to the upper and lower parts of the plate C, so that their free ends bear evenly against the under side of the cushion d. This makes an easy yielding 55 pad which responds quickly to any change in pressure due to the movements of the individual.

Attached to the bottom of the base-plate C is a short strap, F, which is passed through 60 one of the slots a in the plate A, and unites with a buckle, f, secured to the upper part of the base-plate C, thus forming a loop. A second belt, G, is slipped loosely through these loops, being provided with a suitable buckle 65 or other means for adjusting it. This belt is of such a width as to be received between the lugs c of the pads by which it is supported.

A strap, H, is attached to each pad by means of a buckle, h, and is formed at its 70 other end into two loops, h', in which are loosely held the two belts B and G. When the truss is put on, these straps pass between the thighs of the wearer, and, being loosely attached to the belts, they will automatically 75 adjust themselves to the various movements of the person. The belts, moreover, are retained in their relative positions and are prevented from slipping apart.

Having thus described my invention, what I 80 claim, and desire to secure by Letters Patent, is—

1. The combination, with the slotted plate A, of the pads having the perforated lugs c passed through the slots in the plate A, the 85 spring-pins C', and a suitable belt, substantially as set forth.

2. The combination, with the slotted plate A, of the belt B, the pads having the perforated lugs c, the spring-pins C', the straps 90 F, and the belt G, substantially as described.

3. The combination, with the slotted plate A, of the belt B, attached to said plate, the pads having the perforated lugs c passed through the slots in plate A, the spring-pins 95 C', the straps F, the belt G, the buckles h, attached to the pads, and the thigh-straps H, having the loops h', through which pass loosely the belts G and B, substantially as described.

4. A pad for a truss, composed of the base- 100

plate C, the plate C², the cover D, clamped between the two plates, the cushion d, and the M-shaped springs E, having a coil at each angle and arranged side by side with their 5 fixed ends secured alternately in opposite sides of the plate C², and their free ends bearing against the under side of the cushion, substantially as and for the purpose set forth:

In testimony whereof I affix my signature in presence of two witnesses.

JOACHIM WILKE.
